CLAIM

The ornamental design for a ball shaped sounding toy, as
shown and described.

DESCRIPTION

FIG. 1 is a perspective view of a ball shaped sounding toy
showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in FIG. 7 depict a portion of the ball shaped
sounding toy that forms no part of the claimed design. The
appearance within the unshaded interior areas visible in FIG.
1 and 6 likewise forms no part of the claimed design.
